UNITED STATES PATENT OFFICE.

JOHN J. CURRAN, OF AUGUSTA, KANSAS.

PRESSURE-STILL.

1,255,714.

Specification of Letters Patent. Patented Feb. 5, 1918.

Application filed May 25, 1917. Serial No. 170,905.

To all whom it may concern:

Be it known that I, JOHN J. CURRAN, a citizen of the United States residing at Augusta, in the county of Butler and State 5 of Kansas, have invented a new and useful Pressure-Still, of which the following is a specification.

This invention has reference to pressure stills for obtaining gasolene or benzene from 10 gas oil, fuel oil, and the like.

The invention comprises a battery of stills arranged to discharge into a separating tank and associated with the battery of stills is another still receiving residuum from the 15 separating tank for redistillation, the result being that there is a conservation of material and of energy employed in treating the material.

The invention will be best understood 20 from a consideration of the following detailed description, taken in connection with the accompanying drawings forming part of this specification, with the further understanding that while the drawings show 25 a practical form of the invention, the latter is not confined to any strict conformity with the showing of the drawings, but may be changed and modified, so long as such changes and modifications come within the 30 scope of the appended claims.

In the drawings:—

Figure 1 is a front elevation of the battery of stills, or tanks.

Fig. 2 is a rear elevation of the battery 35 of stills omitting the condensing tank and stack.

Fig. 3 is a plan view of the battery of stills, the stack and the condensing tanks.

Fig. 4 is an end elevation with some parts 40 broken away and in section.

Fig. 5 is a longitudinal diametric section of one of the stills.

Referring to the drawings, there is shown 45 a structure 1 which may be a cement or other suitable building with a series of furnaces 2 therein. On the cement structure 1 above each furnace is a still 3 of elongated cylindrical shape similar in conformation to an ordinary steam boiler so far as the 50 outer shell is concerned. At suitable points each still 3 is provided with manholes 4 which may follow the usual custom, but which are only diagrammatically indicated in the drawings. Each still is also provided with gages 5, whereby an operator

may ascertain at any time the pressure conditions within the still.

At a suitable point adjacent to but spaced from the battery of stills is a drum 6 in which is located an upright series of horizontal baffle plates 7 through which are numerous perforations 8. It is desirable that the drum 6 be considerably elevated and higher than the stills 3, and, therefore, it may be supported by a tower 9 of any suitable construction, the drawings indicating a steel truss tower. The furnaces 2 all communicate with a stack 10 through suitable flues 11, 12, respectively, so as to dispose of the products of combustion produced in the furnaces.

There is also a condensing tank 13 for receiving the gas driven off from the gas oil, and this tank is mounted on a suitable foundation 14. The tank 13 is of the usual construction employed in condensers and needs no particular description. The condensed gasolene or benzene may be collected in any suitable manner.

The stills 3 are shown as arranged in a 80 group of ten, although as before stated such particular number is not obligatory. There is also another still 3^a which may be mounted upon the same foundation 1 and is provided with a furnace 2^a similar to the furnaces 2.

All the stills 3 communicate with a supply pipe 15 and all are provided with outlet pipes 16 each containing a valve 17, the outlet pipes 16 in turn communicating with 90 other or trunk pipes 18 leading into the drum 6 at a point below the perforated baffles 7. To the top of the drum 6 there is connected another pipe 19 which at the other end leads into the condenser tank 13 and 95 contains a cut off valve 20. The drum 6 is arranged intermediately of the series of stills 3 and hence that still 3 midway of the length of the series has its pipe 16 directly entering the drum 6 instead of communicating therewith by way of the pipes 18. The pipe 15 enters the respective stills 3 through other pipes 21 which may be so arranged as to force the oil into the still in the form of a spray.

Each still has a steam pipe 22 entering it and provided with a coil or coils 23 extending along the bottom of the still within the latter.

The additional still 3^a is similar to the 110

stills 3 except that the pipe 15 does not communicate with it. Instead of such an arrangement there is a pipe 24 leading from the bottom of the drum 6 into the top of the still 3^a, and in this pipe there is interposed a cut off valve 25. Leading from the still 3^a is another pipe 26 with a valve 27 therein and this pipe leads and opens into the tank 13, near which the pipe is provided with a valve 28 like the valve 20 in the pipe 19. The still 3^a has manholes 4 and a gage 5 like the other stills.

Gas oil is driven into the stills 3 in any suitable manner through the pipes 15 and 21, entering these stills in the form of a spray. Heat is generated in the furnaces 2 of the stills 3 and may be supplemented by superheated steam entering the stills through the pipes 22 and 23. The heating is continued until about 150 pounds pressure, or even more, is produced in the stills, and then the valves 17 are opened and the gas is allowed to flow from the stills through the pipes 16 and 18 into the drum 6, where the light gases of benzene or gasoline pass through the pipe 19 and through the open valve 20 into the condenser 13 where the gases may be condensed and withdrawn. The heavier distillates pass through the pipe 24 and the then open valve 25 into the tank 3^a in the form of tars or heavy liquids, and in this tank the heavy matters are again cracked by the heat provided, the lighter distillates passing through the pipe 26 by way of the valves 27 and 28, which are then open, into the tank 13, thus adding to the accumulation of gasoline or benzene withdrawn therefrom.

The steam pipes in the stills may be used for steaming out the stills, or, as before stated may be employed for directing superheated steam into the stills to help build up the pressure therein.

The final still 3^a has the advantage of providing for a second cracking of the heavy residuum, thus saving the necessity of a separate tar still and the loss of heat and time in directing the heavy distillates into such a separate tar still. The usual practice of pumping out the residuum to a tar still causes loss of all the heat and a considerable loss of time. By the process of this invention it is feasible to recover the coke from the eleventh or last still and also save the light ends.

For instance, the stills permit obtaining about sixty-seven per cent. of benzene from each still and about twenty-eight per cent. of coke in the last still. The run back from all the stills in the line is to the eleventh still as common to the first ten stills.

What is claimed is:—

1. The combination with a battery of stills, each having means for heating it,

means for feeding the material to be treated to the battery of stills, and a drum communicating with all the stills of the battery for receiving distillates therefrom, of an additional still associated with the battery of stills and fed from the drum, said additional still having means for heating it, and condensing means into which the drum and the last-named still deliver.

2. The combination with a battery of stills, each having means for heating it, means for feeding the material to be treated to the stills, and a drum common to the stills of the battery for receiving distillates therefrom and provided with perforated baffles to permit the rise therethrough of light distillates and the accumulation therein of heavy distillates, of an additional still associated with the battery of stills and having means for heating it, said additional still being in communication with the portion of the drum below the baffles to receive heavy distillates collected in the drum.

3. Means for the production of light hydrocarbon liquid from gas oils, comprising a battery of stills and furnaces, and an additional still and furnace therefor associated with the battery of stills and furnaces, a feed pipe connected in common to all the stills of the battery of stills, a drum common to all the stills of the battery of stills and connecting with each still through a valved discharge pipe individual to the still, said drum having means within it for separating light and heavy distillates, condensing means for light hydrocarbon gases communicating with the drum, a valved pipe connecting the portion of the drum receiving the heavy distillates with the separate still, condensing means for the separate still and a valved pipe connecting the separate still and condensing means therefor, the drum being of a height with respect to the separate still to permit gravitating of the heavy distillates from the drum to the still.

4. Means for the production of light hydrocarbon liquid from gas oils, comprising a battery of stills and furnaces, and an additional still and furnace therefor associated with the battery of stills and furnaces, a feed pipe connected in common to all the stills of the battery of stills, a drum common to all the stills of the battery of stills and connecting with each still through a valved discharge pipe individual to the still, said drum having means within it for separating light and heavy distillates, condensing means for light hydrocarbon gases communicating with the drum, a valved pipe connecting the portion of the drum receiving the heavy distillates with the separate still, condensing means for the separate still and a valved pipe connecting the separate

still and condensing means therefor, the drum being of a height with respect to the separate still to permit gravitating of the heavy distillates from the drum to the still, and all of the stills being provided with pipes for directing steam thereinto.

In testimony, that I claim the foregoing

as my own, I have hereto affixed my signature in the presence of two witnesses.

JOHN J. CURRAN.
